W. S. FERDON

CLOTHES PROTECTOR

Filed April 17, 1922

UNITED STATES PATENT OFFICE.

WILLIAM S. FERDON, OF OMAHA, NEBRASKA.

CLOTHES PROTECTOR.

Application filed April 17, 1922. Serial No. 553,393.

To all whom it may concern:

Be it known that I, WILLIAM S. FERDON, a citizen of the United States, residing at Omaha, in the county of Douglas and State 5 of Nebraska, have invented certain new and useful Improvements in Clothes Protectors, of which the following is a specification.

This invention relates to garment protectors and the primary object of the invention is to provide a novel receptacle having vermin, air, and water proof qualities for receiving and protecting garments.

A further object of the invention is the provision of a garment protector of bag like 15 configuration, having novel means for firmly closing the upper open end thereof, the closure insuring against the entrance of dust, moths and the like into the bag, and serving as means for reinforcing the upper end of 20 said bag.

A further object of the invention is the provision of a novel hanger for supporting the garments in the said bag like protector, the hanger also forming means for preventing 25 the collapsing of said receptacle, when the receptacle is in use.

A further object of the invention is the provision of novel means for supporting the garment hanger within the receptacle, so 30 that the said garment hanger can be conveniently removed from the receptacle when so desired, the said supporting means for the garment hanger being connected with the receptacle in such a manner that the 35 garment hanger can be readily and quickly associated therewith at all times.

A further object of the invention is to provide a vermin and dust proof garment receptacle of simple and inexpensive structure, which has novel means for bracing and reinforcing the said receptacle, at points which would be subjected to greatest wear and strain.

With these and other objects in view, the 45 invention consists in the novel construction, arrangement and formation of parts, as will be hereinafter more specifically described, claimed and illustrated in the accompanying drawings, forming a part of this specification, in which drawings:

Figure 1 is an elevation of the improved garment protector.

Figure 2 is a vertical longitudinal section through the improved protector.

Figure 3 is a central vertical section 55 through the improved protector, taken at right angles to Figure 2 and showing the protector in its open position with the garment hanger removed therefrom.

Figure 4 is an edge or side elevation of 60 the improved garment protector.

Referring to the drawings in detail, wherein similar reference characters designate corresponding parts throughout the several views, the letter A generally indicates the improved garment protector, which includes the outer receptacle B; the novel closure C therefor; the novel garment hanger D; and the means E for supporting 65 the garment hanger.

The receptacle B is of a bag like form, and of such a size as to readily receive wearing apparel, such as overcoats, suits and the like. The receptacle B as shown, includes 70 the side walls 5 and 6 connected by an integral bottom wall 7 and end walls 8, which are preferably of bellows form to permit 75 the expansion and contraction of the receptacle.

The receptacle B, can of course, be made 80 of any desired material, but it is preferred that the receptacle be made of a fabric inner skin 9, and an outer rubber skin 10. If desired, the inner fabric skin 9 can be impregnated with some insecticide, camphor 85 or the like, and it is preferred that some anti-vermin substance be incorporated with the rubber skin 10.

If desired, the lower end of the bag may be provided with reinforcing stays or straps 90 11, which can be secured to the inner surface of the side walls 5 and 6.

The closure C provided for the upper end of the receptacle B includes strips 12 and 95 13, which can either be made of wood or metal. It is contemplated, however, to make the strips 12 and 13 from metal, and these strips are riveted as at 14 to the upper ends of the side walls 5 and 6. The strip 12 is formed from angle iron, and includes an upper horizontally disposed flange 15, which is adapted to overlie the upper edge of the strip 13. In order to provide a tight joint, the material from which the receptacle B is made is lapped over the upper edge of the strip 13, and thus this fabric will be forced into intimate contact with the flange 15. End flanges 16 are also formed upon the 100 105

strip 12 and are adapted to engage the ends of the strip 13. In order to bring the strips 12 and 13 into intimate contact with each other, the strip 12 carries inwardly extending threaded studs 17' which are adapted to extend through openings formed in the strip 13 and thumb nuts 18 are threaded on the studs 17', which are adapted to force the strip 13 into contact with the strip 12. 5 This absolutely precludes the entrance of dust, moisture and insects into the receptacle. The flange 15 of the strip 12 carries a hook 17, which forms means for permitting the clothes protector to be hung up. 10 The novel clothes hanger D which is arranged within the receptacle B for holding the clothes therein, includes a transversely extending supporting bar 20, to which is secured, in any preferred manner, a coat or 15 waist hanger 21. This coat hanger also supports a rail 22, upon which skirts and the like can be conveniently hung. Below the rail 22 is a second smaller rail 23, which is adapted to support trousers and the like. 20 This hanger D is supported by the novel means E within the receptacle which will now be described. The end walls 8 of the receptacle B are provided with reinforcing pads 24, and these pads form seats against 25 which the terminals of the supporting bar 20 are adapted to rest. This supporting bar forms an efficient means for preventing the collapsing of the bag, as it can be seen that the side walls 8 are prevented from collapsing 30 inwardly.

The supporting means E for the clothes hanger D includes a pair of spaced flexible straps 25, which have their upper terminals secured as at 26 to the plates 12 and 13 of 40 the closure C. Thus it can be seen that the pair of straps 25 form substantially U-shaped flexible hangers on which the bar 20 can be readily placed. In order to insure the correct holding of the supporting 45 straps 25 at all times, the same are slotted intermediate their ends, as at 27, for the reception of the shanks of rivets or the like 28. These rivets or the like 28 are provided with T-heads 29, which prevent the withdrawal of the rivets from out of the slots. 50 It can be seen that the slots permit movement of the straps 25, but at the same time tend to hold the same in a spread condition to permit the easy placing of a supporting 55 bar 20 thereon.

In use of the improved receptacle, the clothes are placed upon the garment hanger D in the ordinary manner, and the upper end of the receptacle B is pulled open and 60 the hanger is then inserted within the receptacle, on the supporting straps 25. After the hanger has been placed in the receptacle, the upper end of the bag is closed, as heretofore described.

65 From the foregoing description, it can

be seen that a receptacle has been provided for the reception of wearing apparel, which will effectively prevent the settling of dust on the wearing apparel, and prevent insects such as moths and the like from getting to 70 the fabric from which the garments are made.

Changes in details may be made without departing from the spirit or scope of this invention; but,

75

I claim:

1. A clothes protector comprising a receptacle having an upper open end, depending U-shaped straps positioned in the receptacle and having their upwardly extending arms 80 secured to opposed walls of the receptacle adjacent the upper open end of the receptacle and movable towards and away from each other during opening and closing of the receptacle whereby when the receptacle is 85 open a clothes hanger may be placed in the receptacle and supported by said straps.

2. A clothes protector comprising a flexible receptacle having an upper open end and formed of insect and liquid proof material, depending U-shaped flexible straps having their upwardly extending arms secured to opposed walls of the receptacle adjacent the upper open end of the receptacle and movable towards and away from each 90 other during closing and opening of the receptacle, a garment hanger, and a supporting rod secured to the garment hanger and arranged to engage said straps to suspend a garment hanger within the receptacle. 95

100 3. A garment protector comprising a flexible receptacle including side walls and having an open upper end, U-shaped flexible supporting straps having their arms secured at their terminals to the upper ends of the side 105 walls, a garment hanger, a supporting rod secured to the garment hanger and arranged to engage said supporting straps, and means carried by the side walls of the receptacle for engaging arms of said straps below the secured upper ends thereof.

110 4. In a clothes protector, a receptacle having insect and water proof qualities and including side walls, and end walls, the upper end of the receptacle being left open, a 115 clothes hanger arranged to fit within the receptacle, a supporting rod secured to the clothes hanger, means associated with the receptacle for supporting the rod, the rod extending beyond the ends of the clothes 120 hanger, and reinforcing seats carried by the end walls for engagement by the ends of the rod, the rod forming means for preventing collapsing of the receptacle.

125 5. In a clothes protector, a receptacle formed of liquid and insect proof material including side walls and end walls, a strip carried by the upper end of each side wall with the upper edge portion of one of the said walls extending over the upper edge of 130

one strip, an overhanging flange carried by the other strip arranged to extend over the upper edge of the first strip, end flanges carried by the last mentioned strip for engaging the ends of the first strip, inwardly extending threaded studs carried by one of the strips and arranged to extend through the other strip, securing nuts threaded upon the studs for engaging the outer surface of the adjacent strip, and a hook carried by the overhanging flange carried by one of said strips.

WILLIAM S. FERDON.
